UNITED STATES PATENT OFFICE.

THOMAS J. GARRITY, OF PHILADELPHIA, PENNSYLVANIA.

VENTILATED HOOD.

1,071,223.

Specification of Letters Patent.

Patented Aug. 26, 1913.

Application filed October 16, 1912. Serial No. 725,980.

To all whom it may concern:

Be it known that I, THOMAS J. GARRITY, a citizen of the United States, residing at Philadelphia, in the county of Philadelphia and State of Pennsylvania, have invented 5 certain new and useful Improvements in Ventilated Hoods, of which the following is a specification.

My invention relates to improvements in 10 ventilated hoods, and more particularly to an improved construction of hood adapted to be worn by painters and the like who work in close confined and gaseous spaces which allows a supply of fresh air to the 15 workman without any undue pressure and discomfort incident thereto.

A further object is to improve upon the construction disclosed in my pending application filed May 22, 1912, and given Serial 20 No. 699,059.

With these and other objects in view, the invention consists in certain novel features of construction and combinations and arrangements of parts as will be more fully 25 hereinafter described and pointed out in the claims.

In the accompanying drawings: Figure 1 is a view in side elevation illustrating my improvements in operative position. Fig. 2 30 is a view in longitudinal section through the center of the hood showing the supply pipe and the belt in elevation. Fig. 3 is an enlarged fragmentary sectional view illustrating the valve controlling the supply of air 35 and secured to the belt. Fig. 4 is a top plan view of the inner helmet shown in Fig. 2. Fig. 5 is a view in side elevation of the inner helmet. Fig. 6 is a view in side elevation partly broken away illustrating a modified 40 form of helmet, and Fig. 7 is a view in horizontal section on an enlarged scale on the line 7—7 of Fig. 6.

My improved device comprises an inner helmet 1 and an outer helmet 2 spaced apart 45 by reason of the shape of the inner helmet as will be hereinafter explained. A flexible apron 3 is secured over the outer hood, and is provided with a transparent section 4 located in front of the user's face, so that he 50 may observe the work. This apron is provided with arm holes 4^a adjacent its lower edge, so that the apron is adapted to receive the arms of the user, and by thus positioning the same is held in proper position. The inner helmet 1 is provided with outwardly 55 projecting hollow ribs 5 which extend from

a point near the center at the top to the lower edge of the helmet. These ribs are formed integrally and operate to space the helmets apart as it is to be understood the outer helmet 2 rests and fits upon the ribs 5. These ribs, as above stated, terminate short of the center of the helmet at the top, so that they provide an ample air space into which a pipe 6 discharges the air. This pipe is secured through the outer hood 2 and the flexible apron 3, and is bent so as to conform in shape to the shape of the outer hood. The pipe 6 terminates at one side of the device, and is connected to an air supply 70 hose 7 which is located preferably between the arm and body of the user, and has a regulating valve or cock 8 which is secured in a clamp 9 on a belt 10, the latter being located around the waist of the user.

It is to be understood that the hose 7 will be connected to any source of air supply, so that the air is forced into the space between the hoods, and is deflected downwardly so that the user breathes a supply 80 of fresh air at all times regardless of the conditions around him. This air is not in a confined space, but flows freely downward through the open lower end of the apron, but is sufficiently strong to keep out the 85 impure gases. A flexible apron 11 is secured to the inner helmet and extends down the back of the user's head and over his ears to protect this portion of his head from the incoming air. Inside the inner helmet, 90 a sweat band 12 is provided having an adjustable lacing 13 therein so that it may be made to fit any size head. By reason of the hollow ribs 5 on the inner helmet, a supply of air is permitted to enter the inner 95 helmet and keep cool the head of the user, hence these ribs have a double function, namely, they space the helmets apart to allow a free circulation of air downwardly between them, and they also operate as air 100 inlets to keep the head cool.

In the modification illustrated in Figs. 6 and 7, I employ a metallic helmet which is of general spherical form comprising two members 14 and 15 connected at their upper 105 ends by a hinge 16. The member 14 has a transparent section 17 through which the user may view his surroundings, and when provided with my improved helmet 1, he will be thoroughly protected from the air 110 which is blown downwardly through the supply pipe 18 communicating with the top

of section 14, and he can also keep his head cool by reason of the air which flows through the ribs 5. The back section 15 is designed to be opened to allow the helmet 5 to be readily placed in position on the head, and the two sections throughout their edge are rabbeted as shown at 19 to form a tight joint. Spring catches 20 are connected to the inner face of one of the members and 10 locked with the other member when the members are brought together, and push buttons 21 are provided to operate the catches to release them when it is desired to open the helmet. The lower end of the helmet 15 which is positioned around the neck or upon the shoulders of the user has a flange 22 around which the apron 23 may be secured. I have shown snap buttons 24 for the purpose.

20 Various other slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

30 1. A device of the character described, comprising inner and outer helmets, a depending apron secured to the outer helmet, said inner helmet having integral ribs on 35 its outer face spacing the helmets apart and

forming air channels inside the inner helmet and between the helmets, substantially as described.

2. A device of the character described, comprising inner and outer helmets, a depending apron secured to the outer helmet, and said inner helmet having its outer wall formed with integral hollow outwardly projecting ribs contacting with the inner surface of the outer helmet and providing air spaces 40 between the helmets and between the head and the inner helmet when the latter is in operative position, substantially as described.

3. A device of the character described, comprising inner and outer helmets, a depending apron secured to the outer helmet, said inner helmet having integral ribs on its outer face spacing the helmets apart 55 and forming air channels inside the inner helmet and between the helmets, said ribs extending from the lower edges of the inner helmet to a point short of the center of the helmet at the top, whereby an air space 60 is formed at the center of the inner helmet between the same and the outer helmet, substantially as described.

In testimony whereof I have signed my name to this specification in the presence of two subscribing witnesses.

THOMAS J. GARRITY.
